(57) **CLAIM**

The ornamental design for a case for tablet and keyboard, as shown and described.

DESCRIPTION

FIG. 1 is a front perspective view of a case for tablet and keyboard showing our new design.

FIG. 2 is a rear perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The features shown in broken lines in the drawing figures depict features that form no part of the claimed design.

1 Claim, 8 Drawing Sheets
